SMOKING PIPE

Frank Hodgekins Silverthorne, New York, N. Y.

Application July 6, 1935, Serial No. 30,069

2 Claims. (Cl. 131—12)

The invention relates in general to a smoking pipe of the multi-chambered stem type and the invention specifically relates to an improvement in the stem element or stem inserts which define the chambers. More specifically identified, the invention relates to that type of pipe stem which is provided adjacent the bowl with a chamber for receiving smoke from the bowl and incidentally trap therefrom the oily and tarry tobacco condensate juices, hereinafter referred to as the oil trap or condensing chamber, and from which chamber smoke is drawn into a smoke cooling chamber in or adjacent the bit end of the stem and wherein the smoke is permitted to circulate before being withdrawn and into which is discharged any saliva or mouth moisture from the smoker.

The primary object of the invention is to provide an improved and simplified form of pipe of the type outlined which will be maintained "sweet" while in use; which can be easily cleaned; and particularly from which the trapped juices, either those from the tobacco bowl or those from the mouth of the user, may be readily and quickly drained from time to time as may be necessary.

The present disclosure particularly features the forming of the stem in sectional parts which may be readily separated from each other and when separated provide exposed, easily cleaned surfaces which can be scoured with the ordinary pipe cleaners.

Smoking pipes as now generally constructed become objectionable largely because the briar wood of which they are usually constructed readily absorbs the oily and tarry tobacco condensate and give rise to what is commonly referred to as a strong pipe. It has been suggested heretofore to line the condensing chamber of such pipes with some form of metal liner and which, of course, acts to prevent the contamination of the wood, but as heretofore constructed, these metal lined chambers have been designed to permit the smoke to pass therefrom but have not been provided with any means to facilitate the cleaning of the same whenever it is desired to discharge the pipe of its accumulated juices.

Accordingly, another object of the invention is to provide as part of the stem insert, a combined funnel and pouring nozzle which will permit and facilitate the emptying of oils from the condensing chamber whenever the outer end section forming the bit end of the stem is removed for this purpose.

Various other objects and advantages of the invention will be in part obvious from an inspection

of the accompanying drawing and in part will be more fully set forth in the following particular description of one form of pipe embodying the invention, and the invention also consists in certain new and novel features of construction and combination of parts hereinafter set forth and claimed.

The accompanying drawing is a view in vertical axial section through a tobacco pipe illustrating a preferred embodiment of the invention.

Referring to the drawing, there is disclosed a tobacco bowl 10 provided with a tobacco chamber 11 and an integrally extending neck 12 forming the inner end of a stem 13, the outer end of which stem is formed by means of a bit 14. The bit is provided with a plug end 15 forming a tenon telescoping in the open end of the neck 12 to form a two section stem.

The neck is provided with a bore extending therethrough which comprises an enlarged outer cylindrical portion 17 terminating at its inner end in a wall 18 through which extends a relatively constricted portion 19 of the neck bore and opening into the bottom of the tobacco chamber.

Referring to the bit 14, it is provided with a bore 21 of relatively small diameter projecting inwardly from which is a tube 22 forming an extension of the bore 21 and projecting towards the bowl end beyond an inner wall 23. The inner end of the bit is counterbored to provide a smoke cooling chamber 24 largely contained in the bit and into which protrudes axially the inner end of the tube 22. It is understood that the structure as thus far described is somewhat conventional and is illustrated herein to show the adaptability of the novel features of the disclosure to a known form of pipe.

The drawing discloses a metallic construction 25 fitted in the neck bore and comprising a thin walled sleeve 26 wide open at its outer end and provided with a wall 27 at the opposite end. A small diameter tube 28 extends through the wall 27, projects into and outlines, or at least partially outlines, the constricted portion 19 of the bore and leads to the bottom of the tobacco chamber 11. The tube also projects to the right of the drawing a material distance beyond the wall 27 into the oil trap or condensing chamber 29 outlined by the sleeve 26.

The open end of the sleeve is closed by means of a plug like partition 30 of a readily removable unit 31, preferably formed of aluminum or Bakelite. The partition 30 forms the right end of the condensing chamber 29 and the left end clo-

sure of the smoke cooling chamber 24. The unit 31 includes a long tube 32 projecting integrally from the partition 30 and extending therefrom a material distance into the cooling chamber in axial alignment with and spaced slightly from the tube 22 carried by the bit. This long tube is designed to constitute a pouring nozzle or drain for discharging the condensing chamber of its oil or other fluid content when the bit is removed from the balance of the stem for this purpose. The tube 32 is of sufficient length to extend a material distance into the cooling chamber and thus provide an annular saliva drip receptacle 33, particularly designed for wet smokers. The long tube provides a finger piece or handle by means of which the unit as a whole may be withdrawn from the sleeve and for the purpose of facilitating the finger engagement the outer end of the tube is provided with a bulbular enlargement 34 to prevent the finger slipping off the end of the tube.

The side of the partition 30 facing the condensing chamber is provided with a conical funnel-like surface 35 designed to receive drip which 25 may hug the inner wall of the sleeve 26 and discharge the same through the bore 36 of the pouring nozzle 32. The bore 36 should have a conducting capacity not only sufficient to convey the smoke therethrough in the normal operation 30 of the pipe but should also have capacity sufficient to permit the flowing therethrough of the heavy liquid parts of the tobacco condensate. It is not intended in this structure that the heavy 35 tars which settle in the condensing chamber be poured therefrom through the bore 36. These tars are best removed from time to time by withdrawing the unit from the sleeve and cleaning its inner surface with some rugged form of 40 cleaning device or pipe cleaner. However, the lighter liquids can be more frequently discharged from the condensing chamber simply by removing the bit 14 which thus exposes the pouring nozzle and by merely tipping the shank or stem of the pipe downward the more flowable portions 45 of the condensates may be quickly ejected; the bit restored in place and thus the pipe is cleaned to this extent and ready for renewed operation.

The metal parts and preferably the chamber lining shell 26 are preferably made of an aluminum alloy which functions to quickly dissipate 50 heat from the bowl end of the stem. Oils and tars taken out of the smoke in the condensing chamber are prevented from entering the bowl and wetting the tobacco; therefore the tobacco 55 may be smoked to the bottom of the bowl with nothing left but ash. However, the construction is designed so that if the smoker drools saliva while smoking it will be trapped in the chamber 33 at the lower end of the smoke cooling chamber in the event that the smoker habitually 60 smokes with the bowl downward at a lower level than the bit or into the right end of the cooling chamber about the area into which the tube 22 protrudes in the event that the smoker habitually 65 smokes with the bowl elevated.

While there have been shown, described and pointed out in the annexed claims, certain novel features of the invention, it will be understood that various omissions, substitutions and changes 70 in the form and details of the device illustrated and in its operation may be made by those skilled in the art without departing from the spirit of the invention.

I claim:

1. A pipe comprising a bowl having a shank, and a bit, the shank having a bore therethrough, said bore having a restricted opening at its inner end communicating with the bowl, a chamber, and an enlarged portion extending from the chamber to the outer end of the shank, said chamber having a diameter greater than that of the communicating passage and less than that of said enlarged portion, a trap positioned in the chamber, said trap comprising a cylindrical shell and a spout, said spout constituting a closure for one end of the shell and having an opening therethrough communicating with the interior of the shell, a tube extending through the opposite wall of the shell and in alignment with and fitting into the restricted opening of the bore, said bit having a communicating passage of small diameter at the mouth end thereof and of a larger diameter from an intermediate point 20 in the length thereof to the opposite end of the bit, the diameter of the latter passage being greater than the external diameter of the adjacent end of the spout, said spout extending from the shell and projecting into the latter passage, 25 said bit having a reduced portion fitting into the largest diameter portion of the shank bore and abutting the adjacent end of the shell, the communicating passage of small diameter in the bit having a tube fitted therein projecting into its 30 adjacent and larger diameter communicating passage and spaced from the longitudinal walls thereof, said tubes and spout all being in alignment and spaced from each other whereby any liquids and precipitations in the smoke may be 35 released from the smoke during its passage from the bowl to the tip of the bit, the shell constituting a condensation receiving chamber and the large diameter passage of the bit constituting a 40 smoke cooling chamber.

2. A pipe comprising a bowl having a shank and a bit, said shank having a bore therethrough and a chamber, said chamber having a diameter greater than that of the bore, said chamber having a spout constituting a closure for one end thereof, said spout having an opening therethrough communicating with the interior of the chamber, said bit having a communicating passage of small diameter at the mouth end thereof and of a larger diameter from an intermediate point in the length thereof to the opposite end of the bit, the diameter of the latter passage being greater than the external diameter of the adjacent end of the spout, said spout extending from said chamber and projecting into the latter passage, said bit having a reduced portion fitting into the shank and abutting the closure for the chamber, the chamber constituting a condensation receiving chamber and the large diameter passage of the bit constituting a smoke 50 cooling chamber, whereby when the pipe is inclined with the tip at the lower end for the removal of the tip, liquid material in the cooling chamber may be retained for discharge separately from the liquid material in the condensation receiving chamber, said condensation receiving chamber being adapted to completely discharge the liquid therein through said spout when the pipe is suitably inclined.

FRANK HODGEKINS SILVERTHORNE.
